DESIGN FOR A COMBINED WAFFLE IRON AND TRAY

Andrew S. Knapp, Belleville, Ill., assignor to Knapp-Monarch Company, St. Louis, Mo., a corporation of Missouri

Application August 20, 1935, Serial No. 58,215

Term of patent 7 years

To all whom it may concern:

Be it known that I, Andrew S. Knapp, a citizen of the United States and a resident of the city of Belleville, in the county of St. Clair and State of Illinois, have invented a new, original, and ornamental Design for Combined Waffle Iron and Tray, of which the following is a specification,
reference being had to the accompanying drawing,
forming part thereof.

Figure 1 is a top plan view of a combined waffle
iron and tray illustrating my design.

Figure 2 is a front elevational view of the same;
and

Figure 3 is an end elevational view of the same.

I claim:

The ornamental design for a combined waffle
iron and tray, substantially as shown.

ANDREW S. KNAPP.
